UNITED STATES PATENT OFFICE.

HEINRICH BRITTINGER, OF OFFENBACH, GERMANY.

SPIRAL-DRILL-GRINDING MACHINE.

Application filed May 5, 1923. Serial No. 636,990.

To all whom it may concern:

Be it known that I, HEINRICH BRITTINGER, a citizen of Germany, residing at Offenbach, Germany, have invented certain new and useful Improvements in Spiral-Drill-Grinding Machines, of which the following is a specification.

My invention relates to improvements in grinding machines for twist drills and the device described herein is particularly adapted for the class of grinding machines wherein the grinding wheel bearings are stationary, while the drill holder is moved in such manner that a drill may be ground with correct relief.

In known constructions, oscillating motion of the drill holder is accomplished by means of a single or double cam disc, while simultaneously the drill holder spindle is receiving advancing motion by independent means. In the present invention, both of said motions are produced by one and the same cam disc of special design, resulting in simpler construction and smoother operation of the machine.

Referring to the attached drawings which illustrate my invention in connection with a type of grinding machine wherein the twist drill is held in horizontal position, Fig. 1 shows a vertical section taken on line 1—1 of Fig. 2, Fig. 2 is a plan view with top cover taken off, Fig. 3 shows an enlarged sectional view taken on the same line as Fig. 1 and is illustrating details of the locking device of the drill holder spindle, Fig. 4 shows a vertical section on line 4—4 of Fig. 2, Fig. 5 and Fig. 6 show plan views of the drill holder or casing in different working positions, Fig. 6 in particular is showing a position of grinding with increased relief, Fig. 7 is a horizontal sectional cut showing a spring control for the drill holder, Fig. 8 shows an enlarged section of a part of the machine within a plane through the axis of the drill holder spindle. Fig. 9 shows a section within a vertical plane to the axis of the drill holder on line a b of Fig. 8. Figs. 10 and 11 are sections on line c d of Fig. 8, showing control devices for casing 19 and drill holder spindle 10, Fig. 10 corresponding to the working position of the grinder and Fig. 11 corresponding to the position in which drills may be

exchanged. Figs. 12 and 13 respectively are diagrams, showing the action of coupling and uncoupling or releasing the spring control for casing 19, Fig. 12 corresponding to position shown in Fig. 10 and Fig. 13 corresponding to position shown in Fig. 11, indicating how bolt 24 may slide off the inclined surfaces 27 and 28 of the respective webs 25 and 26, as will hereafter be more fully explained.

The machine, as shown, may be driven from a shaft 1 (Figs. 1 and 2), a pulley 2 being belted to a pulley 3, which latter may be mounted on a shaft, carrying a grinding wheel 34. A twist drill holder or casing 19, including a drill holder spindle 10, may be operated by means of pulleys 4 and 5, a belt connecting the latter pulleys being kept under tension by idlers 6. A bevel gear 35 being driven by the pulley 5, may drive a bevel gear 7, the latter being connected by a vertical shaft 36 to a bevel gear 8, which in turn may drive a bevel gear 9, the latter being mounted loosely on a drill holder spindle 10. The gear 9 may have claws 11 at one end, capable of engaging corresponding claws 11 of a cam disc 13, which may be mounted on a sleeve 12 (Figs. 1 and 3), sliding on the latter and driving the drill holding spindle 10 by means of a key 14 (Fig. 3). The other face of cam disc 13 may carry claws 37. By means of levers 15 (Fig. 1), and 16 (Fig. 4), the cam disc 13 may be coupled to gear 9, the latter thus driving the drill holding spindle 10. Said cam disc 13 (Fig. 4), may have one or more cams, but with the arrangement herein shown and for standard twist drills, two are required. Against said cam disc rests one end of a bolt 17 (Figs. 4 to 6), the latter preferably having a roller at each end; the other end of the bolt may bear against a stationary part 32, the latter having a sliding surface 39 along which said bolt may slide. Said part 32 may be arranged adjustable so that the angle formed by the surface 39 with the center line of the pin can be changed. An angular lever 18 may have two arms, one of said arms being connected by a link 40 to the bolt 17, while the other one of said arms may bear against a ring 20, which latter may be tight on the drill holder spindle.

Said drill spindle, cam disc, gear wheel 9 between claws 37, only a slight turn of the spindle will cause the key to snap into place and to lock the spindle.

Other details of the machine, as supports, hand feed etc. are well known and are therefore only shown diagrammatically, needing no special explanation.

In explaining the particular operation of my device, it is clear, that while the drill holder spindle and cam disc rotate, an oscillating motion of said casing 19, and of the drill holder spindle 10 being located therein, must result. Simultaneously with this oscillating motion, the rotating drill holder spindle performs an advancing motion, the latter being caused through the action of lever 18. This combined oscillating, rotary and advancing motion of the drill holder spindle, enables to grind the drill point with relief while using stationary grinding wheel bearings. If the slide 32 is locked in the position shown in Fig. 5, the angle of oscillation of the drill holder or casing is α . If the slide 32 is however locked in position shown in Fig. 6, the angle of oscillation is α plus θ . In other words, while the oscillating motion, being caused through the action of the cam disc, is constant, after being regulated, such regulation is possible by the adjustment of slide 32. As a result the motion of the drill holder spindle may be so controlled that a drill may be ground with any desired relief.

While my drawings show a horizontal drill holder spindle, which is preferable, the spindle may be operating at any angle, or may be vertical. The cam disc, as shown, has two cams, but it may have one or more cams, according to the nature of the drill to be ground. My invention is mainly adapted for twist drill grinding machines having stationary bearings for grinding wheel, but I do not wish to limit my claims to using stationary bearings.

Various modifications may be made in the invention without departing from the spirit thereof and the present exemplification is to be taken as illustrative and not limitative thereof.

Having thus described my invention, I claim:

1. In a spiral drill grinding machine, a drill holder spindle, mounted rotatably, a cam disc arranged revolvably with said spindle, a stationary slide, means being provided for interconnecting the said parts in such manner, that said cam disc, while revolving with said spindle, simultaneously produces oscillating and reciprocating motion of said spindle.
2. In a spiral drill grinding machine, a drill holder spindle, mounted rotatably, a cam disc arranged revolvably with said spindle, a stationary slide, means being provided for interconnecting the said parts in such

5 10 15 20 25 30 35 40 45 50 55 60 65 70 75 80 85 90 95 100 105 110 115 120 125 130

manner, that said cam disc, while revolving with said spindle, simultaneously produces oscillating and reciprocating motion of said spindle, and means for regulating the oscillating motion of said spindle.

3. In a spiral drill grinding machine, a casing, a drill holder spindle, mounted rotatably within said casing, a cam disc arranged revolvably with said spindle, a stationary slide, means being provided for interconnecting the said parts in such manner, that said cam disc, while revolving with said spindle, produces oscillating motion of said casing and simultaneously produces oscillating and reciprocating motion of said spindle.

4. In a spiral drill grinding machine, a casing, a drill holder spindle, mounted rotatably within said casing, a cam disc arranged revolvably with said spindle, a stationary slide, means being provided for interconnecting the said parts in such manner, that said cam disc, while revolving with said spindle, produces oscillating motion of said casing and simultaneously produces oscillating and reciprocating motion of said spindle, and means for regulating the oscillating motion of said spindle.

5. In a spiral drill grinding machine, a cam disc, a drill holder spindle, and a casing, said disc and said spindle being mounted rotatable within said casing, means producing oscillating motion of said casing and simultaneously producing oscillating and advancing motion of said spindle, said means including said disc, a bolt 17, a slide 32, and a lever 18, substantially as and for the purpose set forth and specified.

6. In a spiral drill grinding machine, a cam disc, a drill holder spindle, and a casing, said disc and said spindle being mounted rotatable within said casing, means producing oscillating motion of said casing and

simultaneous-producing oscillating and advancing motion of said spindle, said means including said disc, a bolt 17, a slide 32, a web 25 having a sliding surface 27, a web 26 having a sliding surface 28, means for pressing said casing towards said bolt 17 and the latter against said slide 32, and means for automatically uncoupling said casing, substantially as and for the purpose set forth and specified.

7. In a spiral drill grinding machine, a cam disc, claws 37 on said disc, a drill holder spindle, said disc being arranged to rotate with said spindle, a pin 30 being stationary, a key 29 being arranged to swing around said pin and adapted to enter between said claws if said disc is shifted axially, means being provided for allowing said key to be raised if the same is in such a position that it can not enter between said claws if said disc is shifted axially and means whereby said key automatically snaps between said claws if said spindle is slightly turned, substantially as and for the purpose set forth and specified.

8. In a spiral drill grinding machine, a cam disc, a drill holder spindle, and a casing, said disc and said spindle being mounted rotatable within said casing, means producing oscillating motion of said casing and simultaneously producing oscillating and reciprocating motion of said spindle, said means including said disc, a bolt 17, a slide 32, the latter being arranged adjustably, a lever 18, and means for pressing said disc against said bolt and the latter against said slide.

HEINRICH BRITTINGER.
